UNITED STATES PATENT OFFICE.

GEORGE L. PIERCE, OF BROOKLYN, NEW YORK, ASSIGNOR TO A. G. SPALDING & BROS.,
OF NEW YORK, N. Y., A CORPORATION OF NEW JERSEY.

SHOE.

Application filed March 25, 1924. Serial No. 701,769.

To all whom it may concern:

Be it known that I, GEORGE L. PIERCE, a citizen of the United States, and a resident of Brooklyn, in the county of Kings and State of New York, have invented certain new and useful Improvements in Shoes, of which the following is a specification.

My present invention relates to improvements in shoes of the type known as "turned", having rubber soles, and is designed more especially for embodiment in athletic shoes, though not limited to such use.

The invention aims to provide an improved connection between the rubber outsole and the shoe proper, and comprises the novel construction hereinafter described and particularly defined by the claims appended hereto.

An embodiment of my invention is illustrated in the accompanying drawings, in which:—

Figure 1 is a side elevation of my improved shoe.

Fig. 2 is a section on line 2—2 of Fig. 1, and

Fig. 3 is a section taken on a similar line but showing the shoe before being turned.

Referring by reference characters to this drawing, the numeral 1 designates the upper, which may be of any suitable material, being shown in the drawing as of canvas or duck, and being provided with a toe cap 1^a of suitable material, such for example as leather. The main sole or what I may properly term an intermediate sole indicated at 2, is preferably composed of leather, and is united to the upper by stitching, indicated at 3, in the manner customary in turned shoes, which is well understood by those skilled in the art.

Prior to the application of the sole to, or its connection with the upper, I adhesively secure to the sole member 2 one edge of a welt strip 4 which preferably comprises a strip of rubberized fabric or what is known to the trade as friction fabric, whereafter

the sole member and upper are juxtaposed and stitched together as described.

After the shoe is turned, an outsole of rubber, preferably of crêpe rubber, as shown at 5, is applied and adhesively retained in place, preferably by the interposition of a layer of rubberized fabric, as indicated at 6, and thereafter the welt strip 4 is turned down over and adhesively secured to the peripheral edge of the sole, whereby a very firm union is effected and separation of the sole at the edge effectively prevented.

The shoe is provided with the customary insole indicated at 7.

Having thus described my invention, what I claim is:

1. In a turned shoe an upper and an intermediate sole stitched together, a strip of suitable material having one edge lying between the edge of the upper and the edge of the intermediate sole, and secured by the connecting stitches, and a rubber outsole, the free edge of said strip being adhesively secured to the edge surface of the rubber sole.

2. In a turned shoe an upper and an intermediate sole stitched together, a strip of suitable material having one edge lying between the edge of the upper and the edge of the intermediate sole, and secured by the connecting stitches, and a rubber outsole, a layer of rubberized fabric adhesively securing said outsole to the main sole.

3. The herein described method of making a turned shoe which consists in adhesively securing one margin of a welt strip to one face of a sole member adjacent the edge thereof, uniting said strip and sole member with said upper by stitches, turning the shoe, thereafter adhesively applying an outsole, and turning the welt strip down over and adhesively securing it to the edge of the sole.

In testimony whereof I affix my signature.

GEORGE L. PIERCE.
